[57] CLAIM

The ornamental design for a structural element for furniture, as shown and described.

DESCRIPTION

FIG. 1 is a perspective view taken from the top, front and left side of a structural element for furniture embodying my new design, in the form of a seat back for a chair;

FIG. 2 is a front elevational view thereof;

FIG. 3 is a left side elevational view thereof, the right side being the mirror image of the left side shown;

FIG. 4 is a top plan view thereof;

FIG. 5 is a rear elevational view thereof; and,

FIG. 6 is a bottom plan view thereof.

The fragmentary broken line representations of chair elements in FIGS. 1 through 6 are for the purpose of illustration only and form no part of the claimed design.
